US00D942767S

(12) **United States Design Patent** (10) **Patent No.:** **US D942,767 S**
(45) **Date of Patent:** **** Feb. 8, 2022**

(54) **CHAIR ASSEMBLY**

(71) Applicant: **Steelcase Inc.**, Grand Rapids, MI (US)

(72) Inventors: **Bruce M. Smith**, East Grand Rapids, MI (US); **Robert J. Battey**, Middleville, MI (US); **Glen Oliver Löw**, Hamburg (DE); **James N. Ludwig**, Grand Rapids, MI (US); **Gordon J. Peterson**, Rockford, MI (US); **Russell Thomas Holdredge**, Alto, MI (US); **Todd David Krupicewicz**, Alto, MI (US); **Nathan Robert Brock**, Alto, MI (US)

(73) Assignee: **Steelcase Inc.**, Grand Rapids, MI (US)

(**) Term: **15 Years**

(21) Appl. No.: **29/743,380**

(22) Filed: **Jul. 21, 2020**

Related U.S. Application Data

(63) Continuation-in-part of application No. 16/241,439, filed on Jan. 7, 2019, now Pat. No. 10,842,281, which is a continuation of application No. 15/792,974, filed on Oct. 25, 2017, now Pat. No. 10,264,889, which is a continuation of application No. 15/202,107, filed on Jul. 5, 2016, now Pat. No. 9,826,839, which is a continuation of application No. 14/624,850, filed on Feb. 18, 2015, now Pat. No. 9,408,467, which is a continuation of application No. 13/837,031, filed on Mar. 15, 2013, now Pat. No. 8,998,339, which is a continuation-in-part of application No. 29/432,795, filed on Sep. 20, 2012, now Pat. No. Des. 683,150, said application No. 16/241,439 is a continuation-in-part of application No. 15/891,962, filed on Feb. 8, 2018, now Pat. No. 10,206,507, which is a continuation of application No. 15/256,012, filed on Sep. 2, 2016, now Pat. No. 9,918,552, which is a continuation of application No. 14/633,808, filed on

(57) **CLAIM**

We claim the ornamental design for the chair assembly, as shown and described.

DESCRIPTION

FIG. 1 is a perspective view of a chair assembly embodying the present invention;

FIG. 2 is a front view of the chair assembly;

FIG. 3 is a first side view of the chair assembly;

FIG. 4 is a second side view of the chair assembly;

FIG. 5 is a rear view of the chair assembly;

FIG. 6 is a top view of the chair assembly; and,

FIG. 7 is a bottom view of the chair assembly.

The broken lines in the drawings are for illustrative purposes only and form no part of the claimed design.

1 Claim, 7 Drawing Sheets

Related U.S. Application Data

Feb. 27, 2015, now Pat. No. 9,462,888, which is a continuation of application No. 14/029,243, filed on Sep. 17, 2013, now Pat. No. 9,022,476, which is a continuation of application No. 29/432,765, filed on Sep. 20, 2012, now Pat. No. Des. 697,726, and a continuation of application No. 29/432,767, filed on Sep. 20, 2012, now Pat. No. Des. 697,727, said application No. 15/891,962 is a continuation-in-part of application No. 15/619,591, filed on Jun. 12, 2017, now Pat. No. 9,986,848, which is a continuation of application No. 14/678,065, filed on Apr. 3, 2015, now Pat. No. 9,706,853, which is a continuation of application No. 14/029,284, filed on Sep. 17, 2013, now Pat. No. 8,973,990, and a continuation of application No. 14/029,273, filed on Sep. 17, 2013, now Pat. No. 9,167,910, said application No. 15/619,591 is a continuation of application No. 29/432,776, filed on Sep. 20, 2012, now Pat. No. Des. 697,729.
